UNITED STATES PATENT OFFICE.

EDWARD MELCHIOR, OF CHICAGO, ILLINOIS.

ADJUSTABLE SHELF-SUPPORTING BRACKET.

No. 836,045.

Specification of Letters Patent.

Patented Nov. 13, 1906.

Application filed October 19, 1905. Serial No. 283,494.

To all whom it may concern:

Be it known that I, EDWARD MELCHIOR, a citizen of the United States, residing at Chicago, in the county of Cook and State of Illinois, have invented new and useful Improvements in Adjustable Shelf-Supporting Brackets, of which the following is a specification.

My invention relates to adjustable shelf-supporting brackets; and one of its objects is to provide a bracket of this character wherein the hooked keys or members for securing the bracket to the supporting-bar are fixedly related and arranged or projected in reverse directions—that is, the upper key projects upwardly and the lower key downwardly—and wherein the lower key is shorter than the upper key and provided with a downwardly-inclined inner face, thus permitting the application of the bracket to the supporting-bar by inserting the upper or larger key in one of the key-receiving openings of the supporting-bar, by inserting the lower or smaller key in the next adjacent lower key-receiving opening, and by then moving the bracket downward, this downward movement of the bracket serving to direct the lower key behind the opening through which it projects and by virtue of its inclined face firmly locks the bracket in applied position.

Another object of the invention is to provide a bracket of this character wherein the top or shelf-receiving plate has its rear end provided with flanges serving to engage the supporting-bar to prevent the bracket from having any sidewise movement thereon.

A still further object of the invention is to provide the web of the bracket with lugs for engagement with the supporting-bar, to also prevent the bracket from having sidewise movement thereon, it being understood that the bracket may be provided with both the flanges and lugs, or with either of them.

With the above and other objects in view the invention consists in the construction, combination, and arrangement of parts hereinafter fully described, claimed, and illustrated in the accompanying drawings, where-in—

Figure 1 is a view in side elevation, illustrating my improved bracket in applied position. Fig. 2 is a vertical central sectional view thereof, and Fig. 3 is a detail perspective view of the rear end of the bracket.

Referring to the drawings by reference characters, A designates the supporting-bar, and B the bracket, said supporting-bar being

channeled to provide flanges 1 and a connecting-flange 2. The flanges 1 serve to space the connecting-flange 2 from the support to which the bar is secured, while the connecting-flange 2 is provided with a plurality of key-receiving openings 3.

The bracket B comprises, in the main, a web 4 and a top plate 5, the top plate 5 being secured to the web 4 in any manner found desirable. The web 4 has its rear end formed with hooked keys or supporting-bar-engaging members 6 and 7, said keys being fixedly related and arranged or projected in reverse directions—that is, the upper key 6 projects upwardly and the lower key 7 downwardly. The key 6 is of a length greater than that of the key 7, while the key 7 is provided with an inner downwardly-inclined face 8. The formation of the keys 6 and 7 provides the rear end of the web 4 with shoulders 9, said shoulders resting upon the lower walls of the key-receiving openings 3 when the bracket is in applied position.

The bracket is secured in applied position by first inserting the key 6 in one of the key-receiving openings 3, by then tilting the bracket and directing the key 7 in the next adjacent lower opening 3, and by then moving the bracket downward. This downward movement of the bracket serves to direct the key 7 in rear of the connecting-flange 2, and in view of the inclined face 8 of said key the bracket is caused to firmly bind against the connecting-flange 2, and thus firmly lock the bracket in applied position upon the supporting-bar. The shoulders 9 of the web 4 rest upon the lower walls of the key-receiving openings 3, and thereby limit the downward movement of the bracket.

The rear end of the top plate 5 is cut away, as at 10, to provide flanges 11. The flanges are arranged upon each side of the web 4 and are bent downwardly and rearwardly to provide supporting-bar-engaging members 12, which engage the front face of the connecting-flange 2 and prevent the bracket from having any sidewise movement upon the supporting-bar. The rear end of the web 4 is provided at points intermediate the keys 6 and 7 with laterally-disposed supporting-bar-engaging members 13, which also prevent the bracket from having any sidewise movement upon the supporting-bar A.

The bracket may be provided with the members 12 and 13, or it may only be provided with the members 12, the use of the

members 13 being optional, as the members 12 will serve the purpose of preventing any sidewise movement of the bracket upon the supporting-bar.

5 It is apparent from the above description, taken in connection with the accompanying drawings, that I provide a novel and highly-useful adjustable shelf-supporting bracket which may be firmly and rigidly secured in 10 applied position, which is simple and durable of construction, and which may be manufactured and sold at a comparatively low cost.

From the foregoing description, taken in connection with the accompanying drawings, 15 the construction and mode of operation of the invention will be understood without a further extended description.

Changes in the form, proportions, and minor details of construction may be made 20 within the scope of the invention without departing from the spirit or sacrificing any of the advantages thereof.

Having fully described and illustrated my invention, what I claim is—

25 1. In a device of the character described, the combination with a supporting bar provided with key-receiving openings, of a bracket comprising a web and top plate, said web being provided with hooked keys 30 and supporting-bar-engaging members arranged between the keys, and said top plate being also provided with supporting-bar-engaging members.

2. In a device of the character described, 35 the combination with a supporting-bar provided with a key-receiving opening, of a bracket comprising a web and top plate and provided with a key, said plate having its rear end bent downwardly and rearwardly 40 to provide a supporting-bar-engaging member.

3. In a device of the character described, 45 the combination with a supporting-bar provided with a key-receiving opening, of a bracket comprising a web and top plate and provided with a key, said top plate having its rear end cut away and bent downwardly and rearwardly to provide supporting-bar-engaging members.

50 4. In a device of the character described, the combination with a supporting-bar provided with key-receiving openings, of a

bracket provided with fixedly related hooked keys, one of said keys projecting upwardly, while the other of said keys projects downwardly, the construction and arrangement of the openings and keys being such that upon tilting the bracket the upper key may be inserted through one of the openings in rear of the supporting-bar to permit the insertion of the lower key through another opening, whereby upon a downward movement of the bracket both keys will lock the bracket to the supporting-bar.

5. In a device of the character described, 65 the combination with a supporting-bar provided with key-receiving openings, of a bracket provided with fixedly related hooked keys, one of said keys projecting upwardly, while the other of said keys is smaller and 70 projects downwardly, the construction and arrangement of the openings and keys being such that upon tilting the bracket the larger key may be inserted through one of the openings in the rear of the supporting-bar to permit the lower key to be inserted through another of said openings, whereby upon a downward movement of the bracket the keys will 75 lock the bracket to the supporting-bar.

6. In a device of the character described, 80 the combination with a supporting-bar provided with key-receiving openings, of a bracket provided with fixedly related hooked keys, one of said keys projecting upwardly and being longer than the width of the key-receiving openings, while the other of said keys projects downwardly and is shorter than the width of said openings, the construction and arrangement of the openings and keys being such that upon tilting the 85 bracket the larger key may be inserted through one of the openings in rear of the supporting-bar to permit the smaller key to be inserted through another of said openings, whereby upon a downward movement of the 90 bracket the keys will lock the bracket to the supporting-bar.

In testimony whereof I affix my signature in presence of two witnesses.

EDWARD MELCHIOR.
